UNITED STATES PATENT OFFICE

LESLIE A. RUSSELL, OF MILWAUKEE, WISCONSIN, ASSIGNOR TO KOEHRING COMPANY,
OF MILWAUKEE, WISCONSIN, A CORPORATION

BOOM POINT SHEAVE ASSEMBLY

Application filed March 24, 1930. Serial No. 438,522.

The present invention deals with the art of cranes known as the convertible type. These machines are called usually clamshell or dragline cranes, and in recent years such cranes have been designed so that they may be altered in slight particulars whereby the main crane machine may be used to operate a clamshell boom and bucket or a dragline boom and bucket. Usually the same boom is employed but the buckets are changed and the cables are differently reeved and operated.

When a clamshell bucket is used on the boom of such a machine as described, there are employed at the upper end or boom point a series of sheaves, about six in number, over which the cable reeves for the cables that hoist the boom and which handle the bucket pass. When the machine is converted into a dragline machine, four of the sheaves used for clamshell work are utilized, when only a single sheave is needed to carry the hoisting line of the bucket and this sheave should preferably be adapted to pivot about an axis longitudinal of the boom by reason of the manner in which the load of said bucket is received by the particular sheave just described which is known in crane parlance as a fairlead sheave.

Now by my invention I have provided a boom point sheave supporting structure or yoke means that enables me to employ the six sheave arrangement for clamshell work in which two middle sheaves receive the hoisting and crossing lines for the clamshell buckets, said structure being adapted to be changed to remove the said two middle sheaves and permit the substitution of a fairlead sheave for dragline work. This general idea of construction is the essential feature of this invention, but in addition thereto I employ a special design of fairlead sheave in which the axis of the sheave is about on the line with certain swivel mountings of the supporting device for such sheave, whereby in the dragline work and the use of the hoisting cable, the load about the pivotal axis of the fairlead sheave tends to counterbalance the cable boom on the load pivot axis.

With the foregoing general features of construction in mind, therefore, reference

may be had to the accompanying drawings, in which

Figure 1 is a plan view of a preferred construction of my device, illustrating the fairlead sheave mounted in place for use. 55

Figure 2 is a vertical sectional view on the line 2—2 of Figure 1.

Figure 3 is a sectional view on the line 3—3 of Figure 1, some of the parts not being illustrated. 60

Figure 4 is a cross sectional view on the line 4—4 of Figure 2, and

Figure 5 is a plan view showing the convertible device of my invention, with the fairlead sheave and mounting removed and the clamshell hoist and closing line sheaves substituted therefor. 65

Referring now to the drawings, there is provided at the upper end of the boom used for clamshell and dragline crane work, the boom point yoke 1 having the spaced yoke sides or members 2 and 3. Offstanding from the body of the yoke 1 between the sides 2 and 3 are the attaching lugs 4 and 5 which may be secured by suitable fastenings of any kind to the boom structure. 70

The fairlead pulley or sheave 6 is disposed in a fairlead housing designated 7 and carried by a shaft 8 mounted in bearings 32 at opposite sides of said housing. The housing 7 is provided with a removably mounted guard 9 adapted to extend over a portion of the upper part of the pulley or sheave 6 and attached to the housing 7 by cap screws 34, 35, 36, and 37, or the like. The fairlead sheave 6 is flanked on both sides by depending portions 26 and 27 of the housing 7, the latter having a sort of guard function but spaced to permit the cable reeves to work therebetween. The guard 9 is moreover lined by the provision of the openings 38 and 39 and similarly the side or flanking portions are formed with openings 40 and 41. 80

Outboard sheaves 10 and 11 are mounted on the yoke 1 at opposite sides of the boom, being carried by short shafts 14 and 15. The said short shafts may be held in place by any suitable means such as cross pins and the like and are readily removable for purposes to be hereinafter referred to. A bearing 12 at 85

the central portion of the yoke 1 is adapted to receive the upper trunnion or journal member 16 of the fairlead housing 7 in which the fairlead sheave is carried. Opposed to the bearing 12 is a second bearing 13 arranged on the opposite side of the fairlead housing 7, lengthwise of the boom and having laterally extending portions 28, 29, 30, and 31. The bearing 13 is provided to receive the lower trunnion or journal member 17 of the fairlead housing 7 and this bearing is removably mounted on the boom A. Carried by the boom A are fixed bracket members 18, 19, 20, and 21, the members 18 and 19 being provided with aligned bores and the members 20 and 21 being similarly provided with aligned bores. The lateral portions of the bearing member designated 28, 29, 30, and 31 are provided with bores in alignment with the bores in the bracket members. Suitable pins 22 and 33 are provided with holes 23-23 adjacent to their ends and these pins 22 and 33 are mounted in the aligned bores of the supplemental bracket members 18-19, and 20-21 and pass through the said aligned bores in the bearing member 13 to removably mount this bearing member in position. Each pin aforesaid may be secured in place by cotter pins or other similar means 24.

30 The fairlead guard is provided with a suitable cable clearance 25 and the boom attaching lugs 4 and 5 are reinforced by ribs 42 and 44 and also with reinforcing bosses 43 and 45.

35 It will be noted that by simply removing the pins 22 and 33 the bearing member 13 may be readily displaced laterally to release the fairlead housing 7 under which conditions said housing and the fairlead sheave 6 attached thereto may be readily removed bodily.

40 Of course when the fairlead sheave 6 and its mounting parts are employed, the crane, the boom of which is equipped with such structure, is designed for dragline work, the hoisting cable of the dragline bucket passing over and down from the sheave 6 in a self-evident manner. When, however, the fairlead sheave 6 is detached the short shafts 14 and 15 may be removed, and a single long shaft substituted therefor and designated 50 in Figure 5 of the drawings. This long shaft 50 is adapted to support two middle sheaves 51 and 52 which will guide and support the cable reeves of the clamshell bucket, 55 which reeves are commonly known as the hoisting line and the closing line to those versed in this art.

45 Thus by the simple expedient of providing the special detachable mounting for the boom point fairlead sheave of a dragline crane, as set forth herein, the sheave yoke at the point of the boom may be converted into the sheave yoke of a clamshell crane and support the necessary six sheaves for clamshell bucket work in a self-evident manner.

In this operation of conversion, it is only necessary to remove, or replace, as the case may be, the parts supporting the lower bearing of the fairlead sheave housing, and said housing along with its sheave contained thereon.

Having thus described my invention, what I claim as new and desire to secure by Letters Patent of the United States, is—

1. A boom point sheave mounting for dragline, clamshell, and like cranes, comprising, in combination a boom structure, a sheave supporting yoke mounted thereon, outboard sheaves carried by said boom structure and yoke, and a detachable sheave mounting intermediate said outboard sheaves removable for the substitution of other sheave means, whereby the sheave mounting may be converted into one suitable for clamshell work or for dragline work. 75

2. A boom point sheave mounting for dragline, clamshell, and like cranes, comprising, in combination, a boom structure, a sheave supporting yoke mounted thereon, outboard sheaves carried by said boom structure and yoke, a detachable sheave mounting intermediate said outboard sheaves removable for the substitution of other sheave means, whereby the sheave mounting may be converted into one suitable for clamshell work or for dragline work, and a fairlead sheave carried by the sheave mounting above mentioned. 80

3. A boom point sheave mounting for dragline, clamshell, and like cranes, comprising, in combination, a boom structure, a sheave supporting yoke mounted thereon, outboard sheaves carried by said boom structure and yoke, a detachable sheave mounting intermediate said outboard sheaves removable for the substitution of other sheave means, whereby the sheave mounting may be converted into one suitable for clamshell work or for dragline work, and bearing means carried by the boom and said yoke and disposed in longitudinal alignment lengthwise of the boom to support said sheave mounting in a swivelled manner. 100

4. In a boom point sheave mounting for cranes, in combination, a boom point yoke, a boom point to which said yoke is attached, outboard sheaves supported at opposite sides of the boom point by said yoke and boom point itself, inboard sheave means arranged between the outboard sheaves and between the sides of the boom point, and bearings disposed lengthwise of the boom point above and below the plane in which the said sheaves are arranged, one of said bearings being detachable to facilitate the removal and replacement of a boom point fairlead sheave mounting intermediate the outboard sheaves. 115

5. In a boom point sheave mounting for cranes, in combination, a boom point struc- 120

ture, a yoke carried thereby, outboard sheaves supported by the yoke and the boom point structure, an inboard sheave disposed between the outboard sheaves, and mounting means for said inboard sheave comprising bearings in alignment and longitudinally of the boom on a line substantially intersecting the axis of the inboard sheave.

6. In a boom point sheave mounting for 10 cranes, in combination, a boom point structure, a yoke carried thereby, outboard sheaves supported by the yoke and the boom point structure, an inboard sheave disposed between the outboard sheaves, and mounting 15 means for said inboard sheave comprising bearings in alignment and longitudinally of the boom on a line substantially intersecting the axis of the inboard sheave, said sheave mounting comprising a guard provided with 20 an axis to support the inboard sheave, and said guard being equipped with journal members at its upper and lower ends arranged in the bearings aforesaid.

7. In a boom point sheave mounting of 25 the class described, in combination, a boom point yoke, a boom point structure to which the yoke is attached, outboard sheaves at opposite sides of the boom point structure and supported by it and the sides of the yoke, 30 short shafts carried by the yoke and boom point structure, one for each outboard sheave, said shafts being in alignment and displaceable so as to permit the substitution therefor of a long shaft occupying the bearings 35 of the short shafts and extending across the boom point structure, a swivel fairlead sheave disposed between the outboard sheaves and between the sides of the boom point structure, a mounting means for the 40 swivel fairlead sheave comprising a housing having upper and lower journal members, and bearings on the yoke and on the boom point structure above and below the swivel fairlead sheave respectively and arranged 45 to support the journal members of said housing, one of said bearings being detachable so as to facilitate the removal of the swivel fairlead sheave and the substitution for the same of one or more sheaves for 50 clamshell work to be carried by a shaft substituted for the small shafts above mentioned.

8. In a boom point sheave structure, in 55 combination, a boom point, a part carried by the upper end of the boom point provided with a bearing lengthwise of the boom point, a removable bearing carried by the boom point below the previously mentioned bearing and in alignment therewith, a swivel 60 fairlead sheave mounting having journal members carried in said bearings, and a fairlead sheave mounted in the said mounting so that its axis substantially intersects the line of the bearings for the swivel fairlead 65 mounting aforesaid.

9. In a boom point fairlead and sheave assembly, a yoke attachable to the point of a boom, outboard cable sheaves spaced apart and mounted on the yoke, a fairlead mounting having its axis longitudinal of the boom, 70 and a fairlead sheave carried by said axis mounting.

10. In a boom point fairlead and sheave assembly, a yoke attachable to the point of a boom, outboard cable sheaves spaced apart 75 and mounted on the yoke, a fairlead mounting having its axis longitudinal of the boom, and a fairlead sheave carried by said mounting, said fairlead mounting and sheave being removable so that a shaft may be mounted transversely of the yoke to carry the said 80 outboard cable sheaves and other sheaves which will occupy the space between the outboard cable sheaves.

In testimony whereof I affix my signature. 85
